UNITED STATES PATENT OFFICE.

JOHN G. SKINNER, OF OSWEGO, NEW YORK.

ICE-CREEPER.

SPECIFICATION forming part of Letters Patent No. 371,384, dated October 11, 1887.

Application filed March 19, 1887. Serial No. 231,517. (No model.)

To all whom it may concern:

Be it known that I, JOHN G. SKINNER, of Oswego, in the county of Oswego, in the State of New York, have invented new and useful 5 Improvements in Ice-Creepers, of which the following, taken in connection with the accompanying drawings, is a full, clear, and exact description.

This invention relates to the ice-creeper for 10 which I have obtained Letters Patent of the United States No. 340,378, dated February 19, 1886.

The object of my present invention is to protect the foot of the wearer of the ice-creeper 15 from the pressure of the spurs of the creeper-plate when the latter is in its inverted position; and to that end my invention consists in the combination, with the creeper-plate and its pivot, of an attaching-plate provided with bearings for said pivot and formed with extensions or guards terminating with bearings for the spurs of the creeper-plate when in an inverted 20 position, all as hereinafter fully described, and specifically set forth in the claims.

25 In the accompanying drawings, Figure 1 is a side view of that portion of a rubber shoe to which my improved ice-creeper is applied. Fig. 2 is a detached plan view of the attaching-plate of the ice-creeper. Fig. 3 is an edge 30 view of the same. Fig. 4 is a detached inverted plan view of the creeper-plate, and Fig. 5 is a plan view of the blank from which the aforesaid attaching-plate is formed.

Similar letters of reference indicate corresponding parts.

35 A represents the attaching-plate of the ice-creeper provided with perforations *iii* for the reception of rivets, by which it is secured to the under side of the heel of the boot or shoe. Said attaching-plate I form of a blank of sheet-steel or other suitable sheet metal of the shape 40 of an elongated plate having longitudinal incisions *ll*, extending from one end toward the opposite end and a sufficient distance to form a spring-tongue, *t*, between the ears *e e*, on which the creeper-plate B is pivoted, said ears being formed on the side portions of the plate A by bending said portions of the plate into small loops, as illustrated in Fig. 3 of the drawings. 45 The creeper-plate is formed with a heel projection back of its pivot, by which projection

it presses upon the spring-tongue *t*, and is thus forced to lie with its free end normally in proximity to the attaching-plate, and partially in both its operative position and inverted position. 55

The attaching-plate A is of sufficient length to form between the incisions *ll* an extension, *t'*, of the spring-tongue *t*, which extension terminates with the guards or bearings *bb* in such 60 relative positions as to cause them to be interposed between the bottom of the boot or shoe and spurs of the creeper-plate when the latter is in its inverted position, and thus protect the wearer of said boot or shoe from the 65 pressure of said spurs. By the aforesaid incisions the side portions of the attaching-plates are also formed with extensions *aa*, which terminate with the guards or bearings *a' a'*, adapted to receive the pressure of the 70 spurs of the creeper-plate when in its inverted position, and thus further guard against the injury of the foot of the wearer by the pressure of said spurs.

I do not wish to limit myself to forming the 75 described guards on all of the aforesaid portions of the attaching-plate A, inasmuch as the metal of which the said plate is formed may be sufficiently stiff to afford the desired protection by the formation of only one set of 80 guards, either on the tongue-extension *t'* or on the extensions *aa* of the side portions of the plate.

Having described my invention, what I claim 85 as new, and desire to secure by Letters Patent, is—

1. The improved ice-creeper, consisting of an attaching-plate, a creeper-plate hinged on said attaching-plate, and guards on the latter arranged to be interposed between the bottom 90 of the boot or shoe and spurs of the creeper-plate when in an inverted position, substantially as and for the purpose specified.

2. In combination with the creeper-plate and its pivot, the attaching-plate provided with 95 bearings for said pivot and formed with extensions *aa*, terminating with bearings *a' a'* for the spurs of the creeper-plate when in an inverted position, as set forth and shown.

3. In combination with the creeper-plate and its pivot, the attaching-plate formed with the ears *e e*, and with the spring-tongue *t*, and

tongue-extension t' , terminating with bearings b for the spurs of the creeper-plate when in an inverted position, substantially as set forth and shown.

- 5 In testimony whereof I have hereunto signed my name and affixed my seal, in the presence of two attesting witnesses, at Syracuse, in the

county of Onondaga, in the State of New York, this 17th day of March, 1887.

JOHN G. SKINNER. [L. s.]
